BOTTLE

George F. Church, St. Louis, Mo., assignor to Sinalco Aktiengesellschaft, Detmold, Germany, a corporation of Germany

Filed Feb. 1, 1960, Ser. No. 59,216

Term of patent 14 years

(Cl. D58—8)

FIG. 1

FIG. 3

Fig. 1 is an elevational view of a bottle showing my new design;

Fig. 2 is a cross-sectional view thereof taken on the line 2—2 of Fig. 1; and

Fig. 3 is a cross-sectional view thereof taken on the line 3—3 of Fig. 1.

The side not shown is the same as the side shown.

The drawing is shaded to show contrasting colored areas.

I claim:

The ornamental design for a bottle, as shown and described.
